UNITED STATES PATENT OFFICE

EDWARD G. HIGGINSON, OF PROVIDENCE, RHODE ISLAND.

CORNER STAY FOR BOXES.

Application filed July 12, 1921. Serial No. 424,116.

To all whom it may concern:

Be it known that I, EDWARD G. HIGGINSON, a citizen of the United States, residing at Providence, in the county of Providence and State of Rhode Island, have invented certain new and useful Improvements in Corner Stays for Boxes, of which the following is a specification.

This invention relates to corner stays or locks for folding card board boxes, such as the ordinary suit boxes or the like, and the primary object of the invention is to provide a novel corner stay or lock, which is so constructed that the walls of the box can be readily and easily interlocked and held firmly in place against accidental displacement.

A further object of the invention is to provide a novel device for bracing the locking tongues or wings, said bracing device also forming an efficient means for holding the tongues or wings in their locked position, whereby accidental displacement thereof is prevented.

25 A further object of the invention is to provide an improved corner stay for card board boxes and the like, of the above character, which will be durable and efficient in use and one that can be easily manufactured 30 and at a minimum cost.

With these and other objects in view, the invention consists in the novel construction, arrangement and formation of parts, as will be hereinafter more specifically described, 35 claimed and illustrated in the accompanying drawings, forming a part of this specification, in which drawings:

Figure 1 is a plan view of the blank of one portion of a box.

40 Figure 2 is a perspective view of the blank after the same is folded.

Referring to the drawings in detail, wherein similar reference characters designate corresponding parts throughout the 45 several views, the letter A indicates a blank, which is shaped to conform to the desired configuration of the box, and as shown the blank is of substantially rectangular configuration, and is scored longitudinally adjacent to its longitudinal edges as at 5 and 6, to provide the longitudinally extending side walls 7 and 8. The blank is also scored transversely as at 9 and 10 to provide the end walls 11 and 12. The scored 55 portions 5, 6, 9 and 10 also define the bottom or top wall 13 of the box as the case may be.

The longitudinal side walls 7 and 8 terminate at the transverse scored lines 9 and 10, while the end walls 11 and 12 are extended outwardly of the longitudinal scored lines 5 and 6 to form the interlocking wings 14. These wings 14 are of a novel configuration and include the reduced body portion 15 having parallel marginal edges and an angularly extending insertion tongue 16. 60 At the point of connection of the insertion tongue 16 with the body portion 15 of the wings 14, the wings are provided with oppositely disposed inwardly extending V-shaped notched portions 17 and 18. The 65 notched portion 17 defines a hook 19, the purpose of which will be hereinafter more fully described. The V-shaped notch portion 18 defines a penetrating point 20, the purpose of which will also be hereinafter 70 more fully described.

The end walls 7 and 8 are provided adjacent to their corners with substantially angular shaped locking slots 21, the apex portions of which extend toward the outer 75 corners of these walls.

Intermediate the transverse edges of the side walls 7 and 8 and the angular shaped locking slots 21, the longitudinal side walls 7 and 8 are provided with a pair of spaced 80 parallel slots 22, which define bracing strips 23. These slots 22 extend at an angle to the transverse edges of the side walls 7 and 8, which tends to facilitate the insertion of the wings 14 therein. The wings 14 are 85 adapted to be bent at right angles to the end walls 11 and 12, and are divided therefrom by scored lines 25 as is readily apparent by referring to Figure 1 of the drawing.

When it is desired to interlock the end 90 walls 11 and 12 of the side walls 7 and 8, the same are bent angularly on their scored lines 5, 6, 9 and 10, and the inserting tongues 16 are inserted through the slots 22, and then into the angular locking slot 21. The 95 angular related insertion tongues 16 readily slide into the slots 22, and the inserting points 20 defined by the notches 18 facilitates this insertion. Also the angular position of the slots 22 facilitates the insertion 100 of the inserting tongues therethrough. It is to be also noted that one portion of the angular related locking slots 21 extends in parallel relation to the slots 22. The tongues 16 are inserted into the slots 22 so as to position the locking strips 23 on the exterior 105 of the body, and the tongues 16 are in-

serted in the locking slots 21, the hooks 19 thereof will engage on the inner surface of the side walls of the box and prevent the accidental displacement of the inserting 5 tongues therefrom. The strips 23 form an efficient means for holding the insertion tongues 16 in position in the locking slots 21.

From the foregoing, it can be seen that an exceedingly simple corner stay for cardboard boxes has been provided, which will 10 effectively hold the side walls of the box in interlocked position, and facilitating the interlocking of the walls with one another.

Changes in details may be made without 15 departing from the spirit or scope of this invention; but,

I claim:

1. In a box, a pair of walls, an outwardly extending locking wing formed on one of 20 the walls, the other wall having an angular locking slot formed therein and a pair of parallel arranged slots disposed intermediate the transverse edge of the wall and the locking slot, these slots being arranged to 25 receive the locking wing.

2. In a box, a pair of walls, one of the walls having an angular locking slot formed 30 therein and a pair of spaced parallel guide slots disposed between the transverse edge of the wall and the locking slot, the parallel

slots defining a bracing strip, and a locking wing formed on the transverse edge of the other wall including a body portion having parallel marginal edges, and a laterally extending inserting tongue, and a 35 hook formed on the inserting tongue arranged to engage one of the walls of the locking slot.

3. In a box, a pair of walls, one of the walls having an angular locking slot formed 40 therein and a pair of spaced parallel slots disposed between the transverse edge of the wall and the locking slot, one portion of the locking slot being disposed in parallel relation to the pair of spaced parallel guide 45 slots, and its other portion disposed at substantial right angles thereto, the parallel slots defining a bracing strip, a locking wing formed on the transverse edge of the other wall including a body portion having parallel marginal edges and a laterally extending inserting tongue, the body portion being adapted to be disposed in said parallel guide slots and the inserting portion in said angular locking slot, a hook formed on the 50 inserting tongue and arranged to engage one wall of the angular portion of the locking slot.

EDWARD G. HIGGINSON.
